UNITED STATES PATENT OFFICE.

HENRY R. LUTHER, OF NEWTON, MASSACHUSETTS.

RAILWAY-SWITCH.

No. 821,424.

Specification of Letters Patent.

Patented May 22, 1906.

Application filed September 1, 1905. Serial No. 276,732.

To all whom it may concern:

Be it known that I, HENRY R. LUTHER, a citizen of the United States, and a resident of Newton, county of Middlesex, Commonwealth of Massachusetts, have invented certain new and useful Improvements in Railway-Switches, of which the following is a specification, reference being had to the drawings accompanying the same.

10 My invention relates to a railway-switch wherein the body of the switch has a tongue pivoted therein and so arranged as to be moved laterally.

The object of my invention is to provide a 15 pivot for the tongue of a switch so constructed and arranged that lost motion due to wear on the pivot of the tongue incident to its use may be taken up.

Another object of my invention is to produce a tightening device that will tend to 20 pull the pivot-stud down and at the same time tend to press the heel of the switch-tongue against the abutting ends of the track-surfaces.

25 A further object of my invention is to provide a method for securing the tongue of the switch so that it can be replaced with a new one when worn out or broken without disturbing the body of the switch.

30 In the drawings, Figure 1 is a plan view of my improved device, showing the pivot and the tightening device. Fig. 2 is a partial longitudinal sectional elevation through line 22, Fig. 1. Fig. 3 is a cross-sectional elevation through line 33, Fig. 1. Fig. 4 is a plan view of the wedge-plate forming a part of the tightening device.

In the drawings, 1 represents the body part 35 of the switch.

40 2 is a portion inserted in the body part to form the treads and guides of the switch.

3 is the tongue of the switch.

4 represents the point of the switch, and 5 the heel portion, which has formed upon it 45 the downwardly-projecting lug 6.

7 is a groove in the lower end of the lug 6, adapted to receive the wedge-plate 8. The wedge-plate 8 is shaped to conform to the inclined surface 9, formed on the body part 1.

50 10 is a tapering key which is inserted in holes in the said body part 1 and is provided with an inclined surface on one edge adapted to fit against the inclined surface of the end of the wedge 8.

55 11 is an adjusting-screw, which is revolutionally mounted in a lug 13, forming a part of

the box 14. The box 14 is secured in any suitable manner to the body part 1.

12 represents check-nuts threaded and mounted upon the adjusting-screw 11 and 60 serve to hold it in its properly-adjusted position.

15, 15, and 16 represent short rail-sections which are secured to the body part of the switch by the cast-metal portions 17 17. 65

The operation of my device is as follows: A semicircular socket is formed in the portion 2 of the switch adapted to receive the circular heel portion 5 of the switch-tongue 3. There is also a hole formed through the body 70 part 1 and the portion 2 of a size to receive the lug 6. When the tongue is in place, as is shown in Fig. 2, the wedge-plate 8 is inserted so the recess 18 will straddle the neck of the groove 7 and bear upon the lower wall of said 75 groove. Said wedge-plate 8 when in place will bear upon the inclined surface 9 on the body part, so that when it is pressed into the circular groove 7 its lower face will press against the lower wall of said groove, thereby 80 pulling the switch-tongue down and at the same time tending to press it back into its socket. After the wedge-plate 8 is inserted the key 10 is inserted in its bearings and against the outer end of said wedge-plate 8 to 85 press it into the groove 7, and thereby retain the pivot 6 of the tongue 3 firmly in position.

I do not limit myself to the exact form of groove or wedge-plate shown in the drawings, as the form may be changed without departing from the spirit of my invention. 90

Having described my invention, what I claim is—

1. In a railway-switch, a body part; a switch-tongue pivoted in said body part and laterally movable therein; a pivot-stud on said tongue; a groove in said pivot-stud; and means arranged to enter said groove to pull down the pivot-stud and press the heel of the switch-tongue against a socket formed by the 100 abutting track-surfaces.

2. A railway-switch comprising a body part; a switch-tongue pivoted in the body part and laterally movable therein; a pivot-stud in said switch-tongue; a wedge-shaped 105 plate arranged to pull downwardly on the tongue and press it against the ends of the abutting track; and an adjustable tapering key for adjusting said wedge-shaped plate.

3. A railway-switch, comprising a body part, a laterally-movable tongue and a wedge-shaped plate arranged to pull the tongue

down and press it against the ends of the abutting track.

4. A railway-switch, comprising a body part; a laterally-movable pivoted tongue; a wedge-shaped plate arranged to pull the tongue downwardly and press it against the abutting track; and a tapering adjusting-key.

5. A railway-switch, consisting of a body part; a tongue pivoted in said body part; a wedge-shaped adjusting-plate arranged to pull the tongue downwardly and press it endwise; a tapering adjusting-key; and an adjusting-screw.

6. In a railway-switch, a body part; a switch-tongue pivotally mounted in said body part; a wedge-shaped adjusting-plate arranged to adjust the tongue vertically and longitudinally; and means for adjusting said wedge-shaped plate.

In testimony whereof I have hereunto set my hand, in the presence of two subscribing witnesses, this 31st day of August, A.D. 1905.

HENRY R. LUTHER.

Witnesses:

R. P. ELLIOTT,
W. L. O'BRIEN.
